UNITED STATES PATENT OFFICE.

ARTHUR E. GUISE, OF KENMORE, OHIO.

SWITCH-THROWING DEVICE.

1,316,443.

Specification of Letters Patent. Patented Sept. 16, 1919.

Application filed September 21, 1918. Serial No. 255,145.

To all whom it may concern:

Be it known that I, ARTHUR E. GUISE, a citizen of the United States, residing at Kenmore, in the county of Summit and State 5 of Ohio, have invented new and useful Improvements in Switch-Throwing Devices, of which the following is a specification.

This invention relates to a switch throwing device designed to be carried by a car and 10 operated by air under pressure from the air pipe.

One object is to provide, in a device of the character indicated, an arm and mechanism connected therewith and operated from 15 a plunger within an air cylinder, the said arm being designed to engage and throw a weighted rocking device mounted at the side of the track and having operative connection with the movable switch rails.

With the foregoing and other objects in 20 view, the invention consists in the novel construction, combination and arrangement of elements hereinafter described and claimed.

In the drawings,

Figure 1 is a plan view of a track switch, including the devices directly controlling the switch rails, and showing diagrammatically, in connection therewith, the train carried apparatus,

Fig. 2 shows the train carried apparatus in 30 section and elevation,

Fig. 3 is a view in section of a weighted arm to be mounted at the side of the track, and to be thrown by the train carried apparatus, for throwing the switch,

Fig. 4 shows the weighted arm in elevation, the mounting means being in section, on line 4-4 of Fig. 3.

In carrying out my invention I employ a 40 connecting rod or bar 10 which directly controls the switch points or switch rails 12 and 13, the rails of the main track being designated 14 and 15. This bar 10 has pivotal connection at 16 with an angle lever or angle 45 member 18 pivotally mounted at 19 on a stationary element. A connecting rod 20 is pivotally secured to the angle lever at the point 24, a threaded link connection 25 being employed as an element of the pivotal 50 connection. A similar member 26 is provided at the opposite end of the bar and this element 26 is pivoted at 27 to a rocking arm 28. This arm 28 swings about an axis 29 and is provided with a plurality of weighted 55 members 31 and 32 having a rounded sur-

face and preferably being of substantially cylindrical configuration.

The intervening space between members 31 and 32 may be cut away as shown at 33. Elements 31 and 32 are designed to be sufficiently 60 heavy to throw the switch rails when the rocking arm 28 is thrown off center upon the engagement therewith of an operating arm 35 carried by the car. A bracket 37 of any suitable configuration serves to mount 65 the rocking arm and it is secured to a stationary element at the side of the track.

An air cylinder 40 is connected by means of an inlet duct 41 with the air pipe of the train, and within this cylinder is a plunger 70 42 which is movable under air pressure against the tension of spring 43, such spring serving to return the plunger to normal position when the air pressure is relieved.

A lever arm 45 is mounted at its center and 75 has pivotal connection with the socketed link element 46 which in turn is connected by means of a threaded portion with a rod 47 secured to operating arm 35. Lever arm 45 also has pivotal connection with the stem 80 48 upon which the plunger 42 is mounted.

Another rod 47' is pivotally connected with the opposite end of lever 45 and carries an operating arm 35, so that a rocking arm 28 located on either side of the track may be 85 controlled. A given switch requires but one arm 28, but I do not desire to restrict myself to a particular location therefor.

All of the structure having direct connection with the cylinder, including lever arm 90 45, rod 47, and operating arm 35 is mounted on the car, and when arm 35 is thrown outwardly, or into engaging position, it is designed to trip the rocking arm 28, throwing the latter for the purpose of controlling the 95 switch rails.

What is claimed is:

1. In a device of the class described, a fluid pressure device to be carried by the car, an operating arm connected therewith, 100 an angle lever, means connected with the angle lever for controlling the switch rails, a weighted rocking device, means connected therewith and with the angle lever for operating the latter and throwing the switch 105 rails, said rocking device including a plurality of spaced engaging members, adapted for contact with the operating arm.

2. In a device of the class described, a plurality of switch rails, a bar for throwing 110

the latter, an angle lever with which said bar is pivotally connected, a connecting rod adapted to operate the angle lever, a rocking arm having connection with the connecting rod, said rocking arm including a plurality of spaced contact elements having curved surfaces formed on the arm above the axis about which the arm is movable, said contact elements constituting gravity controlled devices by means of which the switch rails are thrown when the contact elements are engaged from either side thereof.

3. In a device of the class described, a fluid pressure controlled device to be carried by a car and including a cylinder having an inlet having connection with the air pipe of a train, a plunger within the cylinder, a stem

therefor, resilient means for returning the plunger to normal position when the fluid pressure is relieved, a pivotally mounted lever arm connected with the stem, a rod pivoted to one end of said lever arm, an operating arm controlled by the rod, and switch moving mechanism including a gravity controlled rocking arm and contact members for engagement by the aforesaid operating arm.

In testimony whereof I affix my signature in presence of two witnesses.

ARTHUR E. GUISE.
